UNITED STATES PATENT OFFICE.

ALFRED C. TYTLER, OF BASIN, WYOMING.

TOY.

No. 911,462.

Specification of Letters Patent.

Patented Feb. 2, 1909.

Application filed April 17, 1908. Serial No. 427,632.

To all whom it may concern:

Be it known that I, ALFRED C. TYTLER, a citizen of the United States, residing at Basin, in the county of Bighorn and State 5 of Wyoming, have invented new and useful Improvements in Toys, of which the following is a specification.

This invention relates to toys, and the object of the invention is to provide a toy 10 comprising a rectangular box having an upper and a lower compartment, the upper compartment being provided with a sliding door having a perforation near its rear end and an annular opening in its front wall, the 15 compartment being adapted for the reception of perfumed flour or powder, the lower compartment being provided with a suitable pipe, a small fan or wheel being pivotally connected to the rear of the box and having 20 its blades in the path of the opening provided by the pipe, and the box being provided with a removable stem adapted to fit either the pipe member or the opening provided within the front wall of the upper 25 compartment, so that a person inserting the stem within the pipe will cause the rotation of the fan or wheel, and by removing the stem from the pipe and inserting it within the opening provided by the upper compartment 30 and blowing within the stem will cause the powder within the compartment to be ejected through the opening provided by the slideable door and against the face of the person blowing within the stem.

To these ends the invention resides in the novel construction and arrangement of elements, hereinafter fully described and claimed.

In the accompanying drawings, Figure 1 40 is a perspective view of a trick box constructed in accordance with the present invention. Fig. 2 is a central longitudinal sectional view of the same. Fig. 3 is a top plan view of the same.

The main object of the present invention 45 is to provide a trick box adapted to serve as a delusion whereby a person acquainted with the working of the device may cause the revolution of a fan or wheel connected 50 with the device by blowing within the stem connected with the lower portion of the device, and by removing the stem from the lower portion of the device and inserting it within an opening provided within an upper

compartment of the device and offering the 55 device to the person upon whom the delusion is to be practiced and causing him to blow within the device, flour or suitably perfumed powder will be ejected through a 60 suitable opening provided in the upper compartment of the device towards the face of the person blowing into the device.

In the accompanying drawings the numeral 1 designates a rectangular box. This box 1 is provided with an upper compartment 2 and a lower compartment 3. The upper compartment 2 has its front wall provided with a suitable opening 4, and its top provided with an elongated cut away portion or opening adapted for the reception of 70 a sliding cover 5. This cover 5 is provided with an opening 6 near its rear end adjacent the rear wall of the upper compartment 2.

The lower compartment 3 is provided with a longitudinally extending pipe member 7, 75 and the side walls of the box 1 are provided with rearwardly extending arms 8 provided with suitable perforations adapted for the reception of suitable trunnions provided upon a fan wheel 9.

A suitable stem 10 is provided for operating the device. This stem 10 is adapted to have one of its ends tightly inserted within the front end of the pipe or tube member 7, and to likewise engage with the opening 4 of 85 the compartment 2. The tube 7 is in direct alignment with the blades of the fan wheel 9, and by inserting the stem 10 within the tube 7 and blowing within the stem the fan 9 will be caused to revolve upon its pivots in the 90 direction of the arrows illustrated in Fig. 2 of the drawings.

The upper compartment 2 is adapted for the reception of perfumed powder or flour, which is inserted within the compartment 95 through the opening in the top wall of the compartment provided by the sliding door 5, and should the stem 10 be removed from position within the tube 7 and inserted within the opening 4 provided by the front of the 100 upper compartment and the stem blown into so as to cause air to enter the upper compartment 2, the flour within the compartment will be ejected through the openings 6, provided in the sliding cover 5, in the direction 105 shown by the arrow in Fig. 2, and toward the face of the operator.

In order to direct the flour directly against

the face of the operator, an inclined chute or pipe 7' is employed, as clearly illustrated in the figures of the drawings.

Having thus fully described the invention 5 what is claimed as new is:

A trick box comprising a rectangular body having an upper and a lower compartment, the upper compartment being provided with an opening in the front wall and a sliding 10 door having a perforation provided with an inclined tube near its rear end, a tube member extending longitudinally through the lower compartment, a fan wheel pivotally

connected with the rear of the device and having its blades within the path of the 15 opening of the tube, and a detachable stem adapted to fit either the tube member or the opening provided in the front wall of the upper compartment.

In testimony whereof I affix my signature 20 in presence of two witnesses.

ALFRED C. TYTLER.
